POWDER DISPENSER CLOSURE FOR VESSEL TOPS

Neil S. Waterman, 60 Bonner St., Stamford, Conn.

Filed Jan. 6, 1964, Ser. No. 78,078

Term of patent 14 years

(Cl. D58—26)

FIG. 6.

FIGURE 1 is a perspective view of a powder dispenser closure for vessel tops embodying the new design and with one of the cover flaps in raised position;

FIGURE 2 is a side elevation of the powder dispenser closure for vessel tops with the cover flaps closed;

FIGURE 3 is an end elevational view of the powder dispenser closure for vessel tops with its second cover flap in raised position;

FIGURE 4 is a top plan view of the powder dispenser closure for vessel tops;

FIGURE 5 is a top plan view of the powder dispenser closure for vessel tops with the cover member removed; and

FIGURE 6 is a bottom plan view of the same with both flaps of the cover closed.

I claim:

The ornamental design for a powder dispenser closure for vessel tops, substantially as shown and described.
